G. F. HUTCHINS.
SPOOLS FOR TUFT YARN CARRIERS,
APPLICATION FILED JUNE 18, 1910.

1,067,656.

Patented July 15, 1913.

UNITED STATES PATENT OFFICE.

GEORGE F. HUTCHINS, OF WORCESTER, MASSACHUSETTS, ASSIGNOR TO CROMPTON & KNOWLES LOOM WORKS, A CORPORATION OF MASSACHUSETTS.

SPOOLS FOR TUFT-YARN CARRIERS.

1,067,656.

Specification of Letters Patent. Patented July 15, 1913.

Application filed June 18, 1910. Serial No. 567,577.

To all whom it may concern:

Be it known that I, GEORGE F. HUTCHINS, a citizen of the United States, residing at Worcester, in the county of Worcester and State of Massachusetts, have invented certain new and useful Improvements in Spools for Tuft-Yarn Carriers, of which the following is a specification.

My invention relates to spools, which may be used on tuft yarn frames and carriers in wide looms for weaving tufted fabrics, and in which two or more spools are used in a single row.

The object of my invention is to improve upon the construction of spools as ordinarily made, of the class referred to.

My invention consists in certain novel features of construction of my improvements as will be hereinafter fully described.

I have shown in the drawing spools of my improved construction, and their bearings, and friction mechanism, combined with a tuft yarn frame and carrier for wide looms, such as is ordinarily used in weaving moquette, or tufted fabrics.

Referring to the drawing:—Figure 1 is a front view of a tuft yarn frame and carrier with my improved spools combined therewith. Fig. 2 shows, on an enlarged scale, a longitudinal sectional view of the spool shown at the left in Fig. 1. Fig. 3 is a section, on line 3, 3, Fig. 2, looking in the direction of arrow *a*, same figure. Fig. 4 is a section, on line 4, 4, Fig. 1, looking in the direction of arrow *b*, same figure. Fig. 5 shows the spool head detached. Fig. 6 is an edge view of the head shown in Fig. 5, looking in the direction of arrow *c*, same figure, and Fig. 7 is a plan view of the movable cap of the bearing shown in Fig. 3, looking in the direction of arrow *d*, same figure.

In the accompanying drawing, 1 is a hollow metal tube with a wood center 1', to which is secured the metal plate 2, which carries the tubes 3, through which the tuft yarns, not shown, from the spools, not shown, pass. Each end of the tube 1 has fastened thereon the upwardly extending rigid arm 4, having thereon the inwardly extending arms 4', which form bearings for the spool gudgeons or journals. The upper ends of the arms 4 are adapted to engage or enter links of the chain carrier, not shown. Spring catches 5 are secured at their

lower ends by a screw 5' on the arm 4, and have a hooked shaped end 5'' on their upper end, to coöperate with the chain carrier which holds and carries the frame, as is customary in looms of the class referred to. 60

All of the above mentioned parts may be of the usual and well-known construction.

I will now describe my improvements.

The spools 6, in case they are used on a tuft yarn frame and carrier of the class referred to, ordinarily have a longitudinally extending square groove 6' therein, to receive a wire or rod, not shown, which attaches the ends of the tuft yarn, not shown, to the spool, when the yarn is to be wound thereon. I have shown in the drawing three spools 6, which are attached together to extend in a single row, and act as one spool, which extends across the width of the loom. The spool heads or ends, which are ordinarily made of wood and are liable to break, are in my improved construction made of metal, preferably of pressed sheet metal, see Figs. 5 and 6. The heads or ends 7 have a center hole 7' punched therethrough to receive the gudgeon or journal of the spool, to be hereinafter described. A square hole 7'' is made in this instance at one side of the center, in line with the longitudinal groove 6' in the barrel 6, by cutting the metal in three places and bending inwardly the lip 7''' thus formed, said lip enters the outer end of the square groove 6', as shown at the right in Fig. 2. In addition to the integral lip 7''', there may be one or more, preferably three triangular shaped integral lips or projections 7'''' formed on the heads or ends 7, by cutting the metal. The prongs or projections 7'''' are bent inwardly and forced into the ends of the barrel or beam 6, when the ends or heads 7 are pressed thereon, as shown in Fig. 2, and act, in addition to the lip 7''', to prevent the heads or ends from turning on the barrel of the spool. 80

The gudgeons or journals 8 of the spools have in this instance the shank portion 8', adapted to extend through the central hole 7' in the head or end 7 and into a central bore 6'' in the wooden barrel 6, and the annular flange or collar 8'' thereon, to press against the outer side of the head or end 7, around the central hole 7'. The reduced end of the journal 8 is screw-threaded, and screwed into a plug 9 of hard wood, until the annular ring or collar 8'' on the journal 90

8 presses against the metal head or end 7, as shown in Fig. 2 at the left, to secure the head or end 7 to the barrel of the spool 6. A pin 10 extends in this instance through a transverse hole in the spool 6 and in the shank 8', and acts to prevent the journal 8 turning in the spool 6.

The gudgeons or journals for the inner contiguous ends of the spools 6, have preferably the enlarged heads 11 and 12, in this instance one of the heads, as 11, is provided with a transverse fin or extension 11', adapted to enter a correspondingly shaped transverse recess in the head 12, making engaging portions, to coöperate with each other, and form a coupling or connection between two contiguous spools, to cause two spools to rotate in unison. Instead of a fin or projection entering a groove, to form a coupling or connection, other forms of connections may be used.

The gudgeons or journals on the inner ends of the spools 6, are secured thereto in the same manner as the gudgeons or journals on the outer ends, as above described.

The bearings, intermediate the end bearings for the gudgeons or journals 8 on the spools 6, are preferably so made that part of the bearing is readily movable, so that the spools may be readily disconnected from the bearings. In this instance the bearings consist of a stand 13 having a foot 13' secured to the tube frame 1. The stand 13 has a curved part 13'' thereon, forming half of the bearing for the enlarged ends of the gudgeons or journals 11 and 12 on the spools 6. The part 13'' has a side extension 13''' thereon, with a screw-threaded hole therethrough. The other half of the bearing consists of a movable cap 14, which is preferably made forked shaped at its lower end, and is hinged or pivotally secured on a stud 14' to the stand 13. The cap 14 has the extension 14'' thereon, with an open end slot 14''' in its end, see Fig. 7, to loosely receive a screw 15, which is screwed into the threaded hole in the side extension 13''' on the bearing 13. Extending upwardly from the part 14 is in this instance a projection 14''', which forms 50 a handle or engaging part for the cap 14.

When it is desired to remove a spool 6, the screw 15 is turned up, as shown by broken lines in Fig. 3, and the slotted end 14'' of the cap 14, through the location of its pivot stud 14', will pass by the head of the screw 15, and the cap 14 will move upwardly and outwardly, as shown by broken lines in said Fig. 3, to leave a free passage for the removal of the enlarged ends 11 and 12 on the gudgeons or journals 8.

The friction mechanism shown in the drawing for the spools 6, consists in this instance of a spring arm 16, see Figs. 1, and 4, which at its lower end is riveted to the arm 4, and extends inwardly, and has preferably

made separate therefrom and attached to its upper end, a circular plate or disk 17, having a hole 17' therethrough, see Fig. 4, for the bearing 4', and the end of the journal 8 of the spool. The disk 17 has preferably upon its inner surface a yielding material 18, see Fig. 1, which may be leather, or other suitable material, which is pressed against the outer heads or ends of the spools, and acts as a yielding friction surface for the spools.

The friction mechanism, shown in the drawings for the spools 6, and above described, forms the subject matter of another application, and is not claimed herein.

It will be understood that the details of construction of my improvements may be varied if desired.

Having thus described my invention, what I claim as new and desire to secure by Letters Patent is:

1. A spool, comprising a barrel with a longitudinal groove in its periphery, having sheet metal heads with a central hole therethrough for a gudgeon or journal, and said gudgeon or journal, and also having a hole at one side of the center, with a lip or extension at one side of said hole, which extends into the end of said longitudinal groove.

2. A spool, comprising a barrel, a sheet metal head having means to prevent the same from turning on said barrel, a gudgeon at one end, having a portion to enter said barrel, and having an enlarged head or outer end with an engaging portion thereon, to coöperate with a corresponding engaging portion on the enlarged head or outer end on the gudgeon of a second spool, and said second spool, said engaging portions forming a coupling to cause two spools to rotate in unison, and the enlarged heads or outer ends of the gudgeons forming the journal for two contiguous spools.

3. The combination with a spool, comprising a barrel, a sheet metal head having means to prevent the same from turning on said barrel, a gudgeon, having a portion entering said barrel, and secured thereto, and having an enlarged outer end or head with an engaging portion thereon, of a second spool extending in line with the first mentioned spool, and having a sheet metal head, and means to prevent the same from turning on said head, and a gudgeon having a portion entering said barrel, and an enlarged outer end or head having an engaging portion to coöperate with the engaging portion on the first mentioned spool, and said engaging portions, forming a coupling to cause the spools to rotate in unison, and the enlarged heads or outer ends forming a journal for two contiguous spools.

4. The combination with a spool, comprising a barrel, a sheet metal head having

means to prevent the same from turning on said barrel, a gudgeon having a portion entering said barrel and secured thereto, and having an enlarged outer end or head with 5 an engaging portion thereon, of a second spool extending in line with the first mentioned spool, and having a sheet metal head, and means to prevent the same from turning on said head, and a gudgeon having a 10 portion entering said barrel, and an enlarged outer end or head having an engaging portion to coöperate with the engaging

portion on the first mentioned spool, and said engaging portions forming a coupling to cause the spools to rotate in unison, and 15 the enlarged heads or outer ends forming a journal for two contiguous spools, and a bearing for said journal, comprising a stationary part, and a movable part connected to the stationary part.

GEORGE F. HUTCHINS.
